CLAIM

The ornamental design for a shoe, as shown and described.

DESCRIPTION

FIG. 1 is a side view of a shoe showing my new design; FIG. 2 is a front perspective view thereof;

FIG. 3 is an opposite side front perspective view thereof; FIG. 4 is an opposite side view thereof; and,

FIG. 5 is a top view thereof.

The broken lines showing the eight circle shaped elements represent eyelets that form no part of the claimed design. The broken lines showing the two racetrack shaped elements form no part of the claimed design. The broken lines depicting the remainder of the shoe form no part of the claimed design.
